UNITED STATES PATENT OFFICE.

GEORGE E. NEUBERTH, OF NEWARK, NEW JERSEY, ASSIGNOR TO UNIVERSAL CASTER & FOUNDRY COMPANY, A CORPORATION OF NEW JERSEY.

CASTER FOR FURNITURE.

No. 900,417.

Specification of Letters Patent.

Patented Oct. 6, 1908.

Application filed May 21, 1908. Serial No. 434,045.

To all whom it may concern:

Be it known that I, GEORGE E. NEUBERTH, a citizen of the United States, residing at Newark, New Jersey, have invented certain 5 new and useful Improvements in Casters for Furniture, of which the following is a specification (Case 1) illustrated by drawings.

The invention relates to the class of casters having a caster-wheel, jaws and pintle 10 adapted to be held and centered in a tubular leg relatively large as compared with the pintle, and provided with means for detachably holding the caster to the leg, for supporting the weight of the leg upon the caster, 15 for centering and supporting the pintle within the leg when in use, and for holding the caster to the leg so it will not drop off when the leg is raised.

The object of the invention is to produce 20 such a caster which shall be simple in construction and operation, comparatively low in cost, and yet which shall utilize the exterior surface of the leg and have holding means acting on such surface for this purpose.

Tubular metallic legs of a given rated size 25 usually vary to a very considerable extent in their internal diameters, and to a much less extent in their exterior diameters; and moreover, the exterior surface being exposed to view is generally finished with more care than the interior, the interior very frequently having ribs, burs, and other projections which are liable to interfere with the accurate fitting of the caster structure thereto.

In the accompanying drawings, a preferred form of the improvement is shown and also some modifications of the same; and from a description of these and the accompanying claims the invention will readily be understood.

In the accompanying drawings Figure 1 is a partial side elevation partly in central section, showing the preferred embodiment of 45 the invention as applied to a tubular leg. Fig. 2 is a plan view and Fig. 3 a side elevation of the retaining spring by which the caster is held in the leg. Fig. 4 is a plan view of an alternative form of spring; and 50 Fig. 5 a cross section of the same on the line 5-5. Fig. 6 is a partial vertical section of a modification of the socket of the caster shown in Fig. 1. Fig. 7 is a plan view below the section 7-7 of Fig. 6. Fig. 8 is a detail

view partly in section showing a modification 55 of certain parts, this specific modification as such being the subject of a separate application Serial No. 430,046 having specific relation to the present more generic one.

In Figs. 1, 2, and 3 B is the caster-wheel, C 60 the jaws and D the pintle of well known form. The pintle is to be laterally and also vertically supported and held detachably or otherwise in a socket or frame member; and I have selected for illustration a socket having a tubular shank E, to the upper end of which is secured a centering disk or head F, and to the lower end of which is secured a leg-supporting disk G and ornamental leg mount H surrounding the lower end of the tubular 70 leg J. The upper end of the pintle is journaled and supported in the upper end of the socket member, which in turn is supported against the interior of the leg which it should approximately fit. The pintle is detachably 75 secured in the socket by the invent spring tongue K which engages it below the slightly enlarged head of the pintle and prevents the pintle dropping out from the socket of the 80 caster structure. The pintle is journaled near its lower end in the lower end of the socket, as shown. Preferably the weight of the leg is carried to the jaws of the caster by the leg-supporting disk G which rests upon ball-bearings, as shown. The leg mount H 85 surrounding and approximately fitting the exterior of the leg J is centered thereupon, thus centering the lower ends of the socket and of the pintle. Contained within and concealed by the leg mount H is a split circumferentially disposed spring L which is inclined or flared outwards so as to present an inclined face to the foot of the leg when the leg is being thrust into the leg mount and cause the spring to expand sufficiently to 95 admit the leg within it. The spring L is to be made slightly smaller than the exterior diameter of the leg so as to grip and hold upon the surface of the leg when in place. The exterior diameter of the spring should 100 be slightly too great to permit its being drawn out of the leg mount (except on being compressed).

The operation of this preferred structure is as follows: The caster socket is preferably 105 placed upon the foot of the leg before the pintle is inserted, and the furniture may be handled, transported, and offered for sale

with such socket members in place and the caster-wheel, jaws, and pintle separated therefrom so as to avoid injury. In placing the socket on the leg the disk F passes into the leg and the lower end of the leg meeting the spring L within the leg mount strikes against the inclined surface M, which, acting like an inclined plane or cam surface, spreads the spring within the leg mount and allows the leg to pass to the position shown in Fig. 1; whereupon the spring L firmly grips the leg and holds itself, the leg mount, and the socket securely in place. When the pintle is thrust into the socket it passes upwards to the position shown in Fig. 1 and the tongue K holds the parts of the caster structure together, the spring L thus serving to secure the entire structure to the leg by its frictional grip on the outer face of the leg.

20 In Figs. 4 and 5 the spring is shown modified by being bent or bulged inwards at three points P to engage the exterior of the leg and provide the inclined surface for expanding the spring instead of the inclined surface M already described.

In Figs. 6 and 7 a different form of circumferential spring is shown consisting of a split annulus R which is convex inwards to receive the leg and to be expanded thereby slightly. The ring is concave outwards so as to straddle and embrace the inturned edge of the leg mount H, which must be large enough to receive the thickness of the spring between it and the external surface of the leg.

35 In Fig. 8 the leg-supporting disk G of suitably resilient material has upturned arms or members forming at once an ornamental leg mount H' and spring arms or members S for directly engaging and gripping the exterior of the leg and thereby holding the caster to the leg. The upper ends of these springs S should be inclined slightly to the leg surface so as to act like inclined planes or cam surfaces in admitting the leg, as already explained.

Various forms of sockets or of spring frames may be substituted within the caster leg under this invention, and I disclaim any present novelty specifically in the caster-wheel, jaws, pintle, tubular shank, or disk F. Obviously also very considerable modification may be made in the number and relation of the parts of the improved caster structure without departing from the invention and the novel principles of operation which characterize it.

I claim the following:

1. A caster for tubular legs provided with means coacting with the exterior surface of the leg for holding it to the leg, and a pintle-supporting frame or socket extending within the tubular leg.
2. A caster for tubular legs having means coacting frictionally with the exterior surface of the leg for securing the caster, and a

pintle-supporting frame or socket co-acting with the interior of the leg.

3. A caster for tubular legs having an interior pintle-supporting frame or socket a leg mount for exteriorly centering the foot of the leg and spring means for acting frictionally on the exterior of the leg.

4. A caster for tubular legs having a leg mount for exteriorly centering the foot of the leg and spring means separate from but confined or held by the leg mount for acting frictionally on the exterior of the leg.

5. A caster having a leg supporting disk centered on the pintle means for centering the pintle against the interior of a tubular leg and means for centering the disk and pintle against the exterior surface of the leg and for producing friction thereon to secure the disk to the leg.

6. A caster having a pintle-supporting frame or socket for the interior of a leg a leg mount by which the caster is held and means for holding the leg mount on the exterior face of the leg.

7. A caster for tubular legs combining a pintle-centering socket, a leg supporting disk, a leg mount, and securing means acting on the exterior surface of the leg to hold the caster to the leg.

8. A caster for tubular legs combining a pintle-centering socket, a leg supporting disk, a leg mount, and securing means acting on the exterior surface of the leg to hold the caster to the leg, said means comprising one or more resilient members presenting an inclined face or faces to the exterior of the leg, whereby the leg may be thrust into the said leg mount and the members caused to yield outwards.

9. A caster for tubular legs combining a pintle-centering socket, a leg-supporting disk, a leg mount, and securing means acting on the exterior surface of the leg to hold the caster to the leg, said means comprising a circumferentially disposed spring.

10. A caster for tubular legs combining a pintle-centering socket, a leg-supporting disk, a leg mount, and securing means acting on the exterior surface of the leg to hold the caster to the leg, said means comprising a spring contained and concealed within the leg mount.

11. A caster for tubular legs having parts for co-acting with the interior of such legs and parts co-acting frictionally with the exterior of the legs to hold the caster thereto by friction.

In testimony whereof I have signed this specification in the presence of two subscribing witnesses, May 20, 1908.

GEORGE E. NEUBERTH.
